UNITED STATES PATENT OFFICE

LOUIS LICHTMAN, OF NEW YORK, N. Y., ASSIGNOR TO CHROMEPLATE, INC., OF NEW YORK, N. Y., A CORPORATION OF NEW JERSEY

HANGER FOR ARTICLES TO BE PLATED

Application filed November 27, 1928. Serial No. 322,223.

This invention is an improvement in hangers for articles to be plated, and more particularly in a hanger for chromium plating, enabling the articles to be supported in the most favorable position for receiving the deposit.

In electro-plating, the article is the cathode, and in order to obtain a maximum of efficiency, there must be a good electrical connection between the article and the hanger, from which the negative lead of the circuit extends.

In certain ware, such as has reduced or pointed ends, as for instance, rollers having trunnions, a firm grip of the article with efficient electrical contact is difficult to obtain. It is desirable in supporting articles of this character that the contact be at a plurality of points well spaced from each other.

One of the primary objects of the present invention is the provision of a type of hanger, especially adapted for supporting ware of the class above described, wherein the engaging element of the hanger is so arranged as to support the article in substantially horizontal position, contacting at a plurality of points, and resiliently pressed toward the article, whereby to insure good conduction.

Another object is the provision in such a hanger of means engaging the trunnions of the rollers, whereby to leave the exposed surface thereof free for the deposit of the metal.

Another object is the provision of a simple and inexpensive construction, adapted to support a maximum of articles in a minimum of space.

With these and other objects in view the invention consists in the construction and novel combination of parts fully described hereinafter, illustrated in the accompanying drawings, and pointed out in the claims appended hereto, it being understood that various changes in the form, proportion, size and minor details of construction within the scope of the claims, may be resorted to without departing from the spirit of the invention.

In the drawings forming a part hereof:—
50 Fig. 1 is a transverse vertical section of

a tank provided with the improved hanger. Fig. 2 is a perspective view of a portion of the hanger.

The present embodiment of the invention is shown in connection with a plating tank 55 1 of the usual construction, having one or more cross bars 2 extending longitudinally or transversely of the tank, and adapted to support the rack forming the subject matter of the present invention.

The improved rack comprises a substantially U-shaped frame, composed of a body 3, and arms 4, each arm having a hanger 5 at its upper end to engage the cross bar. At suitable intervals cross bars 6 are connected with the sides of the frame in parallel relation, and parallel to the body 3 of the frame. These bars 6 are secured to the members 4 of the frame in any suitable manner, as for instance, by screws as shown, or by 70 soldering or welding.

Each bar 6 is provided with a plurality of hangers, each of which is substantially yoke shaped, composed of a body 7 and arms 8. The yoke is formed from wire of suitable 75 gauge, and in the middle of the body the wire is formed into an open ring 9, which fits the bar 6 loosely as shown in Fig. 2. The ring is secured to the bar in any suitable manner, in the present instance, by solder 10, and each arm is provided at its free end with an open ring 11, adapted to receive the pointed or reduced end of the article 12, which in the present instance, is a roller, having trunnions 13.

The arms of each yoke normally converge slightly toward their free ends, and to engage them with the trunnions, it is necessary to spring them outward away from each other. When the roller is placed, the resiliency of 80 the hanger forces the ends into close contact with the ends of the article, thus to provide a good electrical contact. The bars 2, the frame, the cross bars, and the hangers, are all of conducting material.

What is claimed as new is:—

1. A hanger for articles having reduced ends, of substantially yoke shape and provided at the end of each arm with an open ring, the rings of the arms being adapted to 100

receive the pointed ends of the article, the yoke being of resilient material, and the arms normally converging toward their free ends for the purpose set forth.

5 2. A hanger for articles having reduced ends, of substantially yoke shape and provided intermediate the ends of the body, and at the end of each arm with an open ring, the ring of the body being adapted for connection with a support, and the rings of the arms being adapted to receive the pointed ends of the article, the yoke being of resilient material, and the arms normally converging toward their free ends for the purpose set forth.

10 13. A hanger for articles having reduced ends, of substantially yoke shape and provided at the end of each arm with an open ring, the rings of the arms being adapted to receive the pointed ends of the article, the yoke being of resilient material, and the arms normally converging toward their free ends for the purpose set forth, and a supporting bar for the hanger, to which the body is secured.

15 23. 4. A hanger for articles having reduced ends, of substantially yoke shape and provided intermediate the ends of the body, and at the end of each arm with an open ring, the ring of the body being adapted for connection with a support, and the rings of the arms being adapted to receive the pointed ends of the article, the yoke being of resilient material, and the arms normally converging toward their free ends for the purpose set forth,

25 and a supporting bar over which the open ring of the body engages, said ring being secured to the bar.

30 5. A hanger for articles having reduced ends, of substantially yoke shape, and provided at the end of each arm with a hanger for engaging the reduced end of the article, the yoke being of resilient material.

35 Signed at New York city, in the county of New York and State of New York this 5th day of November, A. D. 1928.

40 LOUIS LICHTMAN.
